TOY CONSTRUCTION PIECE

William Kenneth Menke, 415 Park, Glendale, Mo.
63122; John A. Gale, 1050 Edgewood Hills Drive,
Wayzata, Minn. 55392; and Michael D. Latta, 12945
Whitecliffe, Florissant, Mo. 63033

Filed Nov. 29, 1972, Ser. No. 310,253

Term of patent 7 years

Int. Cl. D21—01
U.S. Cl. D34—15 GG

FIG. 1

FIG. 2

FIG. 3

FIG. 1 is a perspective view of a toy construction piece showing our new design;

FIG. 2 is a bottom plan view thereof; and

FIG. 3 is a front elevational view thereof, the sides undisclosed being substantially identical.

We claim:

The ornamental design for the toy construction piece, as shown and described.
